MAGNETIC PULLEY

Karl A. Blind, Thiensville, Wis., assignor to Dings
Magnetic Separator Co., Milwaukee, Wis., a
corporation of Wisconsin

Application December 29, 1947, Serial No. 794,407

9 Claims. (Cl. 209—219)

1

The present invention relates generally to improvements in magnetic pulleys, and relates more particularly to various improvements in the construction and operation of permanently magnetized pulleys especially adapted to separate magnetic pieces or particles from non-magnetic substances contained in layers or burden of limited depth brought into proximity with the pulleys.

It has long been customary to utilize magnetic pulleys cooperating with conveyor belts or the like for various purposes such as the removal of tramp iron in order to protect the working parts of crushers, grinders, pulverizers, and other machinery against breakage; the removal of metal from explosive mixtures so as to prevent sparks and dust explosions or fires; the purification of non-magnetic substances; and the concentration of magnetic materials. As a rule the magnetic tramp iron or particles are intimately embedded within and mixed with a mass of non-magnetic material so that it requires a powerful field of magnetic influence in order to insure effective removal of the magnetic substances while the mixture or burden is being advanced rapidly through the field. Such sufficiently powerful and dependable magnetic fields could heretofore be established and maintained principally with the aid of electromagnets associated with the magnetic pulleys, and while the operation of the electromagnetic type of pulley is quite satisfactory, it is relatively costly to manufacturer and operate, difficult to install, heavy and cumbersome, and requires considerable attention in order to maintain it in efficient operation. I have discovered that most of these objectionable features may be readily eliminated when treating burden or layers of bulk material of limited depth, by utilizing effective permanent magnets instead of electromagnets in such separating pulleys, and that such improved pulleys also possess numerous other advantages.

It is therefore a primary object of my present invention to provide an improved permanently magnetic pulley which obviates all of the above mentioned objectionable features of electromagnetic pulleys, but which is also adapted to constantly maintain an efficient magnetic field of relatively high intensity.

Another object of the present invention is to provide a simple, compact and durable magnetic pulley devoid of electric wires and other accessories, and which may be readily installed and subsequently operated without attention and additional maintenance cost or expense.

A further object of my invention is to provide

2

a dependable permanently magnetic pulley assemblage composed of relatively few simple parts, and which may be manufactured at moderate cost in various sizes and for diverse uses.

Still another object of this invention is to provide a relatively light but powerful magnetic pulley embodying permanent energizing magnets which possess high magnetic energy and are adapted to retain their magnetism for an indefinite period of time.

An additional object of the invention is to provide an improved magnetic pulley which utilizes many interchangeably similar elements adapted to produce pulley units of various lengths by merely adding or removing parts of the assemblage, thus greatly facilitating manufacture of such pulleys and reducing the cost to a minimum.

These and other more specific objects and advantages of the present invention will be apparent from the following detailed description.

A clear conception of the features constituting my invention, and of the mode of manufacturing and of utilizing the improved permanent magnetic pulleys, may be had by referring to the drawing accompanying and forming a part of this specification in which like reference characters designate the same or similar parts in the various views.

Fig. 1 is a longitudinal section through a typical permanently magnetic crowned pulley embodying the present invention, the section having been taken along the irregular line 1—1 of Fig. 2;

Fig. 2 is a transverse section through the magnetic pulley of Fig. 1, taken along the line 2—2; and

Fig. 3 is a perspective view of an assembled magnetic uncrowned pulley of the general type shown in Figs. 1 and 2.

While the invention has been shown and described herein as having been embodied in a typical magnetic pulley assemblage having four annular series each comprising eight permanent magnets formed of "Alnico" metal, it is not my desire or intention to unnecessarily limit the scope or utility of the improvement by virtue of this restricted embodiment since the number and magnitude of these magnet groups or series may be varied throughout a considerable range without departing from the spirit of my invention.

Referring to the drawing, the typical permanently magnetic pulley shown therein, comprises in general an elongated hollow externally octagonal hub 6 having opposite end supporting bushings or inserts 7 secured thereto by welding or

otherwise; four annular series each consisting of eight radially disposed permanent magnetic slugs or blocks 8 the inner ends of which snugly engage the outer plane faces 9 of the hub 6; an outer elongated shoe or pole-piece 10 snugly engaging the outer plane surfaces of each longitudinally alined set of the blocks 8 and being clamped thereagainst by means of cap screws 11; an annular series of elongated parallel spacer bars 12 interposed between the successive parallel pole-pieces 10; an annular end disc or head 14 coacting with each insert bushing 7 and with the adjacent ends of the pole-pieces 10 and spacer bars 12; and an annular series of parallel bolts 15 for retaining the end heads 14 upon the supporting inserts 7 and for clamping these heads against the hub 6, pole-pieces 10 and bars 12.

The elongated hub 6 is preferably formed of ferrous material such as ordinary steel, and may be of any suitable length adapted to accommodate one or more annular series of the magnetic blocks 8 depending upon the length of pulley face desired; and the supporting inserts 7 may be formed of similar material and are bored for coaction with a pulley mounting shaft 16 to which these inserts may be keyed or otherwise firmly attached. The slugs or blocks 8 are all of interchangeably similar formation and are preferably constructed of material such as "Alnico" metal having high magnetic energy and being intensely permanently magnetized; and these blocks 8 are preferably radially disposed and have plane parallel opposite inner and outer end surfaces, the inner of which snugly engage the outer faces 9 of the hub 6 while the outer block surfaces likewise engage the inner plane faces of the adjacent pole-pieces 10. The elongated pole-pieces 10 which coact with the successive alined rows of magnetized blocks 8 are also formed of ferrous metal such as ordinary steel, and the blocks 8 of each row are clamped firmly between the adjacent pole-piece 10 and hub surface 9 by means of intervening cap screws 11 as depicted in Fig. 1.

The cap screws 11 are preferably formed of non-magnetic material such as brass, and the outer end heads of these screws are confined within sockets 17 formed in the pole-pieces 10 and coact with lock-washers as shown. After the cap screws 11 have been properly applied, the sockets 17 may be filled with lead or solder so as to provide a smooth pulley periphery; and the pole-pieces 10 and the blocks 8 must be segregated from each other, this result being accomplished by means of the spacer bars 12 which are also formed of non-magnetic light material such as aluminum. The spacer bars 12 have tapered or key-stone shaped transverse cross-section and are provided with retainer flanges 18 coacting with the inner surfaces of the adjacent pole-pieces 10 as illustrated in Fig. 2, and both the pole-pieces 10 and the bars 12 may be thickened at their medial portions as in Fig. 1 so as to provide a crowned smooth circular pulley face adapted to coact with a material transporting belt in a well known manner. The interchangeably similar circular end heads 14 are also preferably formed of light non-magnetic metal such as aluminum, while the tie-bolts 15 are formed of non-magnetic material such as brass; and the nuts 19 which coact with the bolts 15 to clamp the end heads 14 against the hub 6, pole-pieces 10 and spacer bars 12 should also be provided with lock-washers as shown.

As previously indicated, any desired number

of the magnetic slugs 8 of diverse sizes and shapes, may be provided in each of the annular series, and any desired number of these series may also be provided, depending upon the size, shape and capacity of pulley desired; and when a pulley has been manufactured and assembled as hereinabove described, it may be utilized as follows. The mounting shaft 16 should be journaled in suitable bearings with its axis disposed approximately horizontal, and an endless belt for conveying the burden or mixture of magnetic and non-magnetic materials should be caused to coact with the periphery of the horizontal pulley in a manner whereby the upper stretch or run of the conveyor belt is tangent to the uppermost peripheral portion of the pulley while the adjacent bend of the belt snugly engages the pulley face and advances about the pulley axis.

The intensely magnetized slugs or blocks 8 of the pulley constantly maintain powerful fields of magnetic influence spanning the successive spacer bars 12 and extending a considerable distance outwardly beyond the periphery of the pulley from each longitudinal edge of each pole-piece 10 to the adjacent longitudinal edge of the adjacent pole-piece 10, and these fields are advanced in succession along the conveyor belt bend coacting with the pulley periphery. When a layer of burden is deposited upon the upper belt stretch and is advanced into the path of revolution of this advancing series of magnetic fields, the magnetic pieces or particles of the burden are drawn toward the outer surface of the travelling belt by magnetic influence and are carried entirely around the belt bend, while the non-magnetic ingredients or particles of the layer are cascaded by gravity from the mid-portion of this belt bend and fall free from the conveying surface. The adhering magnetic ingredients of the burden layer are carried downwardly and rearwardly beyond the vertical plane of delivery of the non-magnetic substances, and are ultimately removed from the zone of magnetic influence below and beyond the pulley, whereupon these magnetic pieces or particles drop by gravity from the transporting surface of the belt.

This separation of magnetic and non-magnetic ingredients of the bulk material or burden, is accomplished continuously, automatically and without the aid of electromagnets. In order to obtain the best results, the thickness of the layer of burden must be limited in accordance with the effective magnitude of the magnetic fields but by utilizing permanent magnetic blocks 8 of proper dimensions formed of materials such as "Alnico" metal, layers of burden up to two inches in thickness may be effectively treated commercially. The improved magnetic pulleys may therefore be advantageously utilized for the removal of tramp iron in order to protect machine parts against damage and to prevent dust ignition sparks, and for the purification of non-magnetic substances or concentration of magnetic substances, thus fitting them for diverse uses in various industries.

From the foregoing detailed description it will be apparent that my present invention provides an improved magnetic pulley which besides being simple, compact and durable in construction, is also efficient in operation and flexible in its adaptations. The provision of the hollow hub 6 and light metal spacer bars 12 and end heads 14, reduces the total weight of each pulley to a minimum without sacrificing strength; and the

use of interchangeably similar supporting inserts 7, blocks 8, pole-pieces 10, spacer bars 12, and end heads 14, reduces the manufacturing cost to a minimum and also greatly facilitates assembly of the pulleys. The construction is simplified by eliminating necessity of utilizing electromagnets and the wiring and electrical apparatus required in connection therewith, and by utilizing permanent magnets the pulley will function automatically and most effectively forever and without any attention or maintenance expense. The magnetic blocks 8 also permit manufacture of the improved pulleys in diverse diameters and lengths at but slight additional cost for each selected size, and the completed pulleys may be readily installed and operated by a novice for use on either wet or dry materials.

The opposite end heads 14 provide non-magnetic extensions beyond the path of travels of the conveyor belt, which not only accommodate or compensate for belt wear but also prevent material from entering the space between the belt and the magnetically active face of the pulley; and the non-magnetic spacers 12 serve as bridge bars for the magnetic circuits, thus producing effective field distribution around the pulley periphery. Since the strength of the successive symmetrically disposed poles is exactly alike, the flux will be uniformly distributed throughout the magnetic field at each of the successive gaps, and this is not the case with assemblages utilizing horseshoe shaped magnets instead of blocks 8 such as utilized in my improved pulley assemblage. The improved assemblage also insures maximum and uniform magnetic strength throughout the full effective area of the conveyor belt, and the invention has proven highly satisfactory and successful in actual commercial use.

It should be understood that it is not desired to limit this invention to the exact details of construction or to the precise mode of use, herein shown and described, for various modifications within the scope of the appended claims may occur to persons familiar with the art; and it is also contemplated that specific descriptive terms employed herein be given the broadest possible interpretation consistent with the disclosure.

I claim:

1. In a magnetic pulley, a hub of magnetic material having polygonal cross-section bounded by plane outer surfaces, an annular series of permanent magnets having inner end faces snugly engaging said hub surfaces, a pole-piece of magnetic material snugly coacting with the outer face of each of said magnets and projecting laterally beyond the adjacent outer faces, and a non-magnetic spacer interposed between each adjacent pair of said pole-pieces and cooperating therewith to form the pulley face, said spacers projecting laterally beyond the laterally projecting portions of said pole-pieces inwardly of said outer magnet faces.

2. In a magnetic pulley, a hub of magnetic material, several spaced annular series of interchangeably similar magnets radiating from said hub, a pole-piece of magnetic material coacting with the outer ends of each axially alined set of magnets of the several series and having edges projecting laterally beyond said outer ends, a non-magnetic spacer interposed between each adjacent pair of said pole-pieces and projecting laterally beneath said edges of the adjacent pole-pieces, and non-magnetic elongated clamping

elements interposed between the adjacent magnets for directly securing said pole-pieces to said hub and for holding said spacers in place.

3. In a magnetic pulley, a hub of magnetic material having polygonal cross-section bounded by flat surfaces, several spaced annular series of magnets radiating from said hub and each having an inner face coacting with one of said hub bounding surfaces, an annular series of parallel pole-pieces each coacting with the outer faces of the alined magnets of all of said series and having edges projecting laterally beyond said outer faces, and a non-magnetic spacer interposed between each adjacent pair of said pole-pieces and projecting laterally beneath said edges of the adjacent pole-pieces.

4. In a magnetic pulley, a hub of magnetic material having polygonal cross-section bounded by flat surfaces, several spaced annular series of magnets radiating from said hub and each having an inner face coacting with one of said hub bounding surfaces, an annular series of parallel pole-pieces each coacting with the outer faces of the alined magnets of all of said series and having edges projecting laterally beyond said outer faces, a non-magnetic spacer interposed between each adjacent pair of said pole-pieces and projecting laterally beneath said edges of the adjacent pole-pieces, and elongated clamping elements connecting each of said pole-pieces with said hub between the successive alined magnets of said series.

5. In a magnetic pulley, a hub of magnetic material, several spaced annular series of magnets radiating from said hub, a pole-piece of magnetic material coacting with the outer ends of each axially alined set of magnets of the several series and having opposite edges projecting laterally beyond said outer ends, a non-magnetic spacer interposed between each adjacent pair of said pole-pieces and projecting laterally beneath said edges of the adjacent pole-pieces, and elongated clamping elements connecting each of said pole-pieces with said hub between the successive magnets of each set.

6. In a magnetic pulley, a hub of magnetic material, several spaced annular series of magnets radiating from said hub, a pole-piece of magnetic material coacting with the outer ends of each axially alined set of magnets of the several series and having opposite edges projecting laterally beyond said outer ends, a non-magnetic spacer interposed between each adjacent pair of said pole-pieces and projecting laterally beneath said edges of the adjacent pole-pieces, elongated clamping elements connecting each of said pole-pieces with said hub between the successive magnets of each set, an end head clampingly engaging each end of said hub and the adjacent ends of said pole-pieces and spacers, and other elongated clamping elements connecting said end heads between the successive alined sets of said magnets.

7. In a magnetic pulley, a hub of magnetic material, several spaced annular series of interchangeably similar permanent magnets radiating from said hub, a pole-piece of magnetic material coacting with the outer ends of each axially alined set of magnets of the several series and having opposite side edges projecting laterally beyond said outer ends, a non-magnetic spacer interposed between each adjacent pair of said pole-pieces and projecting laterally beneath said edges of the adjacent pole-pieces, an end head of non-magnetic material clampingly engaging

each end of said hub and the adjacent ends of said pole-pieces and spacers, and elongated clamping elements connecting said end heads and being disposed between the successive aligned sets of said magnets.

8. In a magnetic pulley, a hub of magnetic material having several annular series of permanent magnets radiating therefrom, a pole-piece of magnetic material coaxing with the outer ends of each axially aligned set of radial magnets of the several series and each having opposite edge portions projecting laterally beyond said outer magnet ends, a non-magnetic spacer interposed between each adjacent pair of said pole-pieces and projecting laterally beneath said edge portions of the adjacent pole-pieces, and elongated elements for clamping said pole-pieces to said magnets and for simultaneously retaining said spacers in position.

9. In a magnetic pulley, a hub of magnetic material having several annular series of permanent magnets radiating therefrom, a pole-piece of magnetic material coaxing with the outer ends of each axially aligned set of radial magnets of the several series and each having opposite edge portions projecting laterally beyond said outer magnet ends, a non-magnetic spacer interposed

5 between each adjacent pair of said pole-pieces and projecting laterally beneath said edge portions of the adjacent pole-pieces, and elongated elements disposed between the successive magnets of said series for directly clamping said pole-pieces against the outer ends of said magnets and for simultaneously clamping said magnets to said hub while also retaining said spacers in proper position.
